UNITED STATES PATENT OFFICE.

PHINN W. TOWNSEND, OF DEL RIO, TEXAS.

ADVERTISING NOVELTY.

Application filed August 23, 1927. Serial No. 214,925.

My invention relates to the art of advertising and it particularly has for its object to provide a neat appearing novelty in the nature of a match holder with spaces and 5 visions for advertisements, some of a more or less permanent character, and others changeable at will.

Further, it is an object to provide a match holder of the character stated in which provision is made to hold the matches separately 10 in convenient positions to be taken by one desiring the same.

Further, it is an object of the invention to provide an advertising match holder having 15 a storage chamber in which a reserve supply of matches (boxed or loose) may be kept if desired.

Other objects will in part be obvious and 20 in part be pointed out hereinafter.

To the attainment of the aforesaid objects and ends, my invention consists in the novel 25 details of construction, and in the combination, connection and arrangement of parts hereinafter more fully described and then pointed out in the claim.

In the drawing:

Figure 1 is a perspective view of a preferred embodiment of the invention.

Figure 2 is a central longitudinal section 30 of the same.

Figure 3 is a rear elevation thereof.

In the drawing in which like numerals of reference indicate like parts in all the figures, 35 1 represents the body whose sides 2 provide convenient spaces on which advertisements may be placed. The front end 3 of the body may also serve to carry an advertisement.

The top 4 of the body has a depressed portion 5 of any desired configuration as square, 40 round, or other shape in plan (square being shown in the drawing) and this depressed portion 5 is provided with longitudinal and transverse rows of pockets 6 each adapted to receive an individual match 7 (see dotted lines in Figure 2).

The top 4 is also provided with a depressed

portion 9 separated from the depressed portion 5 by a space 8 adapted to receive advertising matter as indicated in Figure 1.

The body 1 adjacent the depressed portion 9 is provided with grooved slideways 15 in which a glass plate 10 and a removable advertising card 11 may be placed, the card being visible through the glass plate as indicated in Figure 1. In order to enable the card and plate to be removed or changed easily, the body 1 has a portion 12 cut away to expose the card and plate and form a convenient finger recess through which the card and plate may be engaged for the purpose 60 stated.

Beneath the recessed portion 9 of the top of the body and entering from the rear end is a chamber 13 of sufficient volume to contain a number of boxes 14 of matches as a reserve 65 supply.

It is intended that the advertisements on the sides 2, end 3, and top space 8 shall be more or less permanent in character though they may vary in different units, but the advertisement in the depressed portion 9 is 70 preferably such that it can be changed at will simply by removing the card 11 and substituting another therefor.

From the foregoing description, taken in 75 connection with the accompanying drawing, it is thought the construction and advantages of my invention will be clear to those skilled in the art to which it relates.

What I claim is:

In advertising novelties, a body having a flat bottom, sides and ends, and an inclined-plane top, said top having an area provided with a group of individual match stem receiving pockets, the axes of which pockets 85 are parallel one to the other and normal to the face of the body, said area being located at the lower half of the top, and said body having a chamber entering from the deeper end and terminating short of said pockets 90 for the purpose specified.

PHINN W. TOWNSEND.
